DESCRIPTION

U.S. PATENT DOCUMENTS

FIG. 1 is a front elevational view of a catheter showing my new design; the rear side view being a mirror image; and, FIG. 2 is an alternative front elevational view of FIG. 1, showing a top portion in a folded position, the rear side view being a mirror image.

The broken lines shown in FIGS. 1 and 2 are for the purpose of illustrating portion of the catheter that forms no part of the claimed design.

1 Claim, 2 Drawing Sheets

FIG. 1

FIG. 2
